[57] **CLAIM**

The ornamental design for the marine navigation light, as shown and described.

DESCRIPTION

FIG. 1 is a front perspective view of the marine navigation light showing our new design;
FIG. 2 is a right side elevational view of FIG. 1;
FIG. 3 is a left side elevational view of FIG. 1;
FIG. 4 is a front elevational view of FIG. 1;
FIG. 5 is a rear elevational view of FIG. 1;
FIG. 6 is a top plan view of FIG. 1, the bottom view being unornamented;
FIG. 7 is a front perspective view of a second embodiment of the marine navigation light;
FIG. 8 is a right side elevational view of FIG. 7;
FIG. 9 is a left side elevational view of FIG. 7;
FIG. 10 is a front elevational view of FIG. 7;
FIG. 11 is a rear elevational view of FIG. 7;
FIG. 12 is a top plan view of FIG. 7, the bottom view being unornamented;
FIG. 13 is a front perspective view of a third embodiment of the marine navigation light;
FIG. 14 is a right side elevational view of FIG. 13;
FIG. 15 is a left side elevational view of FIG. 13;
FIG. 16 is a front elevational view of FIG. 13;
FIG. 17 is a rear elevational view of FIG. 13; and,
FIG. 18 is a top plan view of FIG. 13, the bottom view being unornamented.
